UNITED STATES PATENT OFFICE.

EMIL M. REFIOR, OF PITTSBURGH, PENNSYLVANIA.

METAL ROLL.

Application filed April 12, 1921. Serial No. 460,671.

To all whom it may concern:

Be it known that I, EMIL M. REFIOR, a citizen of the United States, residing at Pittsburgh, in the county of Allegheny and 5 State of Pennsylvania, have invented certain new and useful Improvements in Metal Rolls, of which the following is a specification.

This invention relates to forming and 10 shaping rolls and more particularly to those used for rolling objects the cross sectional area of which is varied throughout the length thereof and where necessary are geared or meshed to insure their holding 15 and to cause the impressions in the rolls to match as they revolve.

The object of the invention is to so construct a set of rolls that objects of special shape or round, square, flat, hexagon or any 20 other section or combination of sections or where the cross sectional area is not retained throughout the length of the bar to be rolled may be formed and the excess metal which overflows or is pressed out from the impression or die at points where smaller cross 25 sectional areas are produced will be caught in depressions or gutters formed in the faces of the rolls, the flash or excess metal to be trimmed or cut or hot or cold after the bar 30 has been rolled.

Another object is to so position and connect the gutters above referred to that the overflow therein may be readily trimmed or cut from the rolled article.

35 With these and other objects in view, the invention consists in certain novel features of construction as hereinafter shown and described and specifically pointed out in the claims.

40 In the accompanying drawings:—

Figure 1 represents an edge view of one of the rollers constituting this invention with a bar shown in operative position thereon in the impression or groove of the rolls.

45 Fig. 2 is a transverse section through a pair of the rolls constituting this invention a section only of one of which is shown.

Fig. 3 is a transverse section of a slightly different form of roll.

50 Fig. 4 is a detail sectional view of a pair of the rolls showing the larger portion of the impressions grooves or dies in mating relation.

Fig. 5 is a section taken on the line 5—5 of 55 Fig. 4; and

Fig. 6 is a similar view taken on the line 6—6 of Fig. 2.

In the embodiment illustrated in Figs. 1, 2, 4, 5, and 6 a pair of forming rolls 1 and 2 are shown which are mounted to revolve in 60 unison with their peripheries in contact, (see Fig. 2). These rolls are provided with a groove, impression or die conforming to the shape of the article to be formed or rolled by feeding the bar or billet 10 between them. 65 These grooves, impressions or dies comprising a plurality of large grooves 3, four being here shown spaced peripherally equal distances apart and having arranged between and connecting them grooves 4 of smaller 70 cross sectional area, said smaller grooves being flared at their opposite ends as shown at 5. The flared ends of the smaller grooves merge into the larger grooves 3 whereby inclined or tapered shoulders 13 are formed 75 at the junction of the larger parts 11 and the smaller parts 12 of the bar or billet 10 being rolled.

It is to be understood that while the above 80 described form of die or impression is herein shown any other form may be employed, portions of which vary in cross sectional area.

Formed in the peripheral faces of the rolls on opposite sides of each of the smaller 85 grooves 4 and spaced laterally therefrom are flash gutters or troughs 6 corresponding in length to the length of said grooves 4 and connected by shallow conduits 7. These conduits 7 are designed to permit the excess 90 metal produced by the bar 10 passing through the smaller grooves 4 to flow or be pressed out through said conduits into the gutters 6 and form a thin fin of metal 14 which connects the metal in the gutters with the smaller cross sectional part 12 of the bar and is designed to be trimmed or cut off either hot or cold after the bar is taken from the rolls.

In the operation of the rolls a bar 10 is 100 fed between them while they are revolving and the mating dies or grooves in the faces thereof produce the desired shape in the bar so rolled, the excess material which is pressed out when the bar passes through the smaller 105 grooves 4 being caught in the gutters 6. This excess material will provide scrap of a desirable quality without in any way interfering with the proper rolling of the bar and the bar after being rolled may be readily sepa- 110

rated therefrom by trimming or cutting off the thin fin 14 which connects the smaller portions 12 of the bar with the excess caught in the gutters.

5 In the form shown in Fig. 3 larger grooves 3^a of the die are spaced irregular distances apart instead of equal distances as is shown in the other figures, three only of the larger grooves 3^a being here shown connected by 10 smaller grooves 4^a of different lengths otherwise this form is the same as that shown in the other figures.

15 The preferred embodiment of the invention is disclosed in the drawings and set forth in the specification, but it will be understood that any modifications within the scope of the claimed invention may be made in the construction without departing from the principle of the invention or sacrificing 20 any of its advantages.

What is claimed is:—

1. A die of the class described having depressions of varying sizes in its operative face with an overflow receiving recess at one 25 side of each of the smaller depressions connected therewith by shallow conduits.

2. A set of rolls having on the opposed faces thereof, complementary sets of registering forming cavities and further provided 30 with spaced complementary recesses arranged at the sides of and connected with certain of said molding cavities of each roll by conduits.

3. A set of rolls having on the opposed 35 faces, complementary sets of registering molding cavities, certain of said registering cavities shallower than the other, the opposed faces of said rolls being furthermore provided at each side of said shallow molding cavities with spaced complementary recesses 40 connected with said shallow molding cavities by lateral conduits.

4. A set of rolls having opposed faces, each of the opposed faces provided with sets of registering forming cavities, each set comprising a cylindrical cavity, oppositely disposed tapering forming cavities projecting from the termini of said cylindrical cavity, an elongated cylindrical forming cavity leading to one of the tapering cavities, and 50 the said faces of said rolls further provided with a recess at each side of and connected with said elongated cylindrical forming cavity by a lateral conduit.

5. A set of rolls having opposed faces, 55 each of the opposed faces provided with sets of registering forming cavities, each set comprising a cylindrical cavity, oppositely disposed tapering forming cavities projecting from the termini of said cylindrical cavity, 60 an elongated cylindrical forming cavity leading to one of the tapering cavities, and the said faces of said rolls further provided with a recess at each side of and connected with said elongated cylindrical forming cavity by a lateral conduit, said elongated cylindrical cavity shallower than said tapering cavities and short cylindrical cavities.

In testimony whereof, I affix my signature hereto.

EMIL M. REFIOR.
